UNITED STATES PATENT OFFICE.

CLARA BIRCHARD LAMBERT, OF PASADENA, CALIFORNIA.

LIGHT FOR TELEPHONE STANDS.

Application filed April 30, 1928. Serial No. 273,958.

This invention relates to a telephone stand light construction, the primary object of the invention being to provide a light stand so constructed that it may be positioned adjacent to a telephone stand to illuminate the dial or articles supported at the base thereof.

An important object of the invention is to provide a device of this character which will closely engage the telephone associated therewith to the end that the device will not only be practical but will be exceptionally ornamental.

A still further object of the invention is to provide an attachment of this type which will not interfere with the operation of the telephone in any way, and one which may be picked by the user of the telephone, with the telephone.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a perspective view of a light stand constructed in accordance with the invention.

Figure 2 is a side elevational view of a modified form of the invention.

Figure 3 is a plan view thereof.

Referring to the drawing in detail, the device includes a base 5 which is curved so that it will contact with one edge of the base of the telephone with which the device is associated.

Extending upwardly from the base 5 is a standard 6 which terminates at a point adjacent to the upper end of the telephone, the

upper end of the standard 6 lying just below the mouth piece of the telephone, which is shown in Figure 1, in dotted lines.

Extending laterally from the standard 6, is an arm 7 which has a downwardly extended end portion provided with a lamp socket 8 in which an electric lamp 9 is mounted, the lamp being so disposed that light rays will be projected from the lamp downwardly onto the dial of the telephone 55 which is indicated in dotted lines and designated by the reference character 10.

In the form of the invention as shown by Figures 2 and 3 of the drawing, the light stand includes a flat circular base 11 designed to receive the base 12 of the telephone.

The reference character 13 designates a standard that has a laterally extended lower portion 14 secured to the base 11, adjacent to one edge thereof, the laterally extended portion 14 being curved to conform to the shape of the upper surface of the base of the telephone so that it will closely engage the base.

Extending laterally from the upper end of the standard 13 is a curved arm 15 curved around the upper portion of the telephone. The free end of the arm extends downwardly at 16 where it is supplied with a lamp 75 to illuminate the dial of the telephone which is indicated by the reference character 17.

It will also be understood that the standard and arm are hollow, so that the usual electric wires providing the circuit to the so lamp forming a part of the device, may be extended therethrough.

I claim:

A telephone supporting and lighting stand including a flat base to be positioned on a supporting surface, said base being constructed to receive a telephone receiver, an arm extending upwardly and inwardly from the edge of the base, the inwardly extended portion being curved to conform to the cur- 85 90 95

vature of the upper surface of the telephone base and fit thereagainst, a standard forming a continuation of the inwardly curved portion and adapted to rest against the telephone receiver, a laterally extended arm at the upper end of the standard, and curved to fit around the telephone receiver positioned on the base, the last mentioned curved arm terminating in a downwardly curved portion, and a socket on the downwardly curved portion.

In testimony that I claim the foregoing as my own, I have hereto affixed my signature.
